DESIGN FOR A VASE

George A. Sparks and Allan C. Cunningham,
Los Angeles, Calif.

Application October 25, 1946, Serial No. 134,234

Term of patent 3½ years

(Cl. D29—28)

To all whom it may concern:

Be it known that we, George A. Sparks and Allan C. Cunningham, citizens of the United States, residing in the city of Los Angeles, county of Los Angeles and State of California, have invented a new, original, and ornamental Design for a Vase, of which the following is a specification, reference being had to the accompanying drawings, forming a part thereof.

Fig. 1 is a front perspective view of a vase, showing our new design; Fig. 2 is a side elevational view of the vase, and Fig. 3 is a rear elevational view of the vase.

We claim:

The ornamental design for a vase, as shown.

GEORGE A. SPARKS.

ALLAN C. CUNNINGHAM.
